Patented Sept. 17, 1918.

2 SHEETS—SHEET 2.

UNITED STATES PATENT OFFICE.

JAMES ARTHUR JONES, OF ANDERSON, INDIANA.

APPARATUS FOR CLEANING ERASERS.

1,279,350.

Specification of Letters Patent. Patented Sept. 17, 1918.

Application filed October 10, 1917. Serial No. 195,833.

To all whom it may concern:

Be it known that I, JAMES A. JONES, a citizen of the United States, and a resident of Anderson, in the county of Madison and State of Indiana, have invented a new and Improved Apparatus for Cleaning Erasers, of which the following is a full, clear, and exact description.

My invention relates to an apparatus whereby to clean blackboard erasers.

General objects of the invention are to provide an apparatus for the indicated purpose equipped with novel feed means to engage the eraser as it is entered in the apparatus; to provide an effective means to successively beat and brush the eraser as it is advanced by the feed means; and to provide for exhausting the dust.

A more specific object of the invention is to provide the feed means, cleaning means, and fan assembled in compact form and arranged to be driven from a motor.

Reference is to be had to the accompanying drawings forming a part of this specification in which similar reference characters indicate corresponding parts in all the views, it being understood that the drawings are merely illustrative of one example of the invention.

Figure 1 is a plan view with parts in section on the line 1—1, Fig. 2, and others broken away;

Fig. 2 is a longitudinal vertical section on the line 2—2, Fig. 1;

Fig. 3 is a longitudinal vertical section on the line 3—3, Fig. 1.

In carrying out my invention a suitable base 10 is provided, sustaining suitable bearings 13 in which the shaft 11 of a suitable electric or other motor 12 is mounted to turn. The shaft 11 has a crank arm 14, to the wrist pin 15 of which a connecting rod 16 is pivoted, the opposite end of said connecting rod being pivoted to a rocker arm 17 on a rocker shaft 18 mounted in suitable bearings indicated at 19, 19^a.

The shaft 18 carries a resilient beater arm 20 of spring metal, suitably secured to said shaft, there being indicated a bracket 22 on said shaft to which the beater 20 is secured as by a rivet or screw 21. The free end 23 of the beater arm is offset to extend through a vertical opening 24 in the bottom 25 of an open-ended tunnel 26 through which the eraser indicated in part by dotted lines at A in Fig. 2 is adapted to pass.

To feed the eraser, upper and lower rollers 27, 28 are provided, the roller 28 being a positive feed roller which is actuated by the rocking of the shaft 18 for the purpose. In 60 the illustrated example said roller 28 is mounted on the shaft 29 on which is a ratchet wheel 30 engageable by a pawl 31 pivoted as at 32 to a rigid arm 33 on the shaft 18. The upper side of the feed roller 65 28 extends through a vertical opening 34 in the bottom 25 of the tunnel. The upper roller 27 is secured in the forked free end of a vibratable arm 35 secured to a shaft 36, said arm being pressed upon by a spring 37. 70

With the described construction the motor 12 serves to rock the shaft 18 to thus vibrate the end 23 of the beater 20 and simultaneously the feed roller 28 is caused to feed the eraser, indicated at A, with a step by 75 step movement, gradually advancing the eraser over the beater, the yielding pressure of the roller 27 effectively maintaining a proper contact of the eraser with the feed roller.

Resistance to the action of the beater 20 against the eraser is produced by pressure on a roller 38 in advance of a roller 37, said roller 38 being mounted on a swingable arm 39 secured at one end to a shaft 40, the arm 85 being under the pressure of a suitable spring 41, the roller 38 being positioned directly above the offset end 23 of the beater. The numeral 42 indicates a housing or casing on the base 10 for closing the operative parts. 90

In advance of the beater 20 I provide a brush 44 to remove any dust particles adhering to the eraser. Said brush is mounted on a shaft 43 in the top of the casing 42 and extends at its upper side slightly through an opening 45 in the top 25 of the tunnel 26. The brush is driven from the motor 12 in any suitable manner, there being a cross belt 46. In order to exhaust the dust removed from the eraser by the beater 20 and brush 44, a fan 47 is provided, driven by a suitable means from the motor 12 and by a belt 48. An outlet tube 50 leads from the fan casing 49 and may deliver to any suitable dust collector or receptacle, or may have connected therewith a hose 51 to lead to any distant point. 100

It will be noted with regard to the beater 20 that to produce the offset end 23, the beater is bent at such an angle as to insure 110 clearance for the vibration of the beater below the bottom 25 of the tunnel while the

projection of the offset end through the opening 24 will be insured for effective engagement of the said offset end with the eraser A and parallel with the latter.

5 I wish to state in conclusion that although the illustrated example constitutes a practical embodiment of my invention, I do not limit myself strictly to the mechanical details herein illustrated, since manifestly the same can be considerably varied without departure from the spirit of the invention as defined in the appended claims.

10 Having thus described my invention, I claim as new, and desire to secure by Letters Patent:

15 1. An apparatus for cleaning erasers, including a casing, a tunnel on said casing adapted to afford passage of an eraser to be cleaned, yielding pressure rollers one in advance of the other in said tunnel beneath which the eraser may be passed, a feed roller in said casing at the bottom of the tunnel, said bottom having an opening beneath the one pressure roller through which 20 the top of the feed roller projects, a vibratable beater arm having an offset free end, the bottom of the tunnel having a second opening located beneath the second pressure roller, and accommodating the offset end of 25 the beater arm, means to actuate the said feed roller and to vibrate the beater arm, a rotary brush in advance of the beater arm, the bottom of the tunnel having a third opening through which the top of the brush 30 extends to engage the eraser after action by the beater arm, and means to cause suction in said casing and induce an air current from the tunnel through the said openings in the bottom of the tunnel to the said casing to collect the dust arising in the tunnel 35 and at said openings.

40 2. An apparatus for cleaning erasers, including a tunnel adapted to afford passage of an eraser to be cleaned, yielding pressure devices one in advance of the other in the tunnel at the top, beneath which the eraser may successively pass, a feed roller in the casing at the bottom of the tunnel coacting with the first pressure means, a vibratable

beater arm beneath the tunnel, the outer 50 end of said arm being upwardly offset and extending through the bottom of the tunnel beneath the second pressure means, and means to actuate said feed roller and vibratable arm.

55 3. An apparatus for cleaning erasers including a casing, a tunnel on said casing adapted to afford passage of an eraser to be cleaned, a vibratable arm beneath the bottom of the tunnel, said bottom having an 60 opening therein and the free end of the beater arm being offset and extending through said opening, and means to cause a suction from the tunnel through said opening to the casing to collect the dust produced 65 from the action of the beater arm on the eraser.

4. In an apparatus of the class described, a casing, a tunnel on top of the casing adapted to afford passage for an eraser to 70 be cleaned, a rock shaft in the casing beneath the bottom of the tunnel, a beater arm on said shaft, said beater arm having an upwardly offset free end and the bottom of the tunnel having an opening through which 75 said offset end extends, means in the tunnel at the top to yieldingly press the eraser against the bottom of the tunnel, means to feed the eraser through the tunnel past the beater arm, a fan adapted to exhaust the air 80 from the tunnel through the said opening, and means to drive said fan and rock the said shaft.

5. An apparatus for cleaning erasers, including a casing, a tunnel on said casing 85 adapted to afford passage for an eraser to be cleaned, a feed roller in the casing at the bottom of the tunnel, the casing having an opening through which the said feed roller extends to engage the eraser, a rock shaft in 90 the casing adjacent to the feed roller, a beater arm on the rock shaft, the bottom of the tunnel having an opening through which the beater arm projects to engage the eraser, a pawl pivoted on the rock shaft, a ratchet 95 wheel on the feed roller engaged by said pawl, and means to actuate said rock shaft.

JAMES ARTHUR JONES.
